UNITED STATES PATENT OFFICE.

RUSSELL HUFF, OF DETROIT, MICHIGAN, ASSIGNOR TO PACKARD MOTOR CAR COMPANY, OF DETROIT, MICHIGAN, A CORPORATION OF MICHIGAN.

STARTING MECHANISM FOR MOTOR-VEHICLES.

1,114,265.

Specification of Letters Patent. Patented Oct. 20, 1914.

Application filed March 6, 1911. Serial No. 612,705.

To all whom it may concern:

Be it known that I, RUSSELL HUFF, a citizen of the United States, and resident of Detroit, Wayne county, State of Michigan, have invented certain new and useful Improvements in Starting Mechanism for Motor-Vehicles, of which the following is a specification.

This invention relates to motor vehicles and particularly to the mechanism for starting the motor. As is well known, in a motor of the internal combustion type one of the essential elements is an ignition mechanism for causing a spark in the cylinder to explode the charge and usually this ignition mechanism is so constructed that the time of the spark relative to the position of the piston may be varied within certain limits for the purpose of causing early or late ignition. Late ignition is required in starting in order that the motor shall start in the right direction, and early ignition is essential after the motor has been started in order that the charge may be completely fired. In some motor vehicles of today the timing of the ignition mechanism is manually controlled and the judgment of the operator is depended upon to properly advance the spark for the various motor speeds. In the present system, however, the ignition mechanism is so constructed that during the normal operation of the motor the spark is always in an advanced position, thus freeing the operator of the responsibility of properly timing the spark. This system is particularly adapted for commercial vehicle use where drivers of various degrees of intelligence are employed and it is desirable to give the driver or operator as little as possible to take his attention. With the system last mentioned, however, it is necessary to have some means for temporarily retarding the spark for the purpose of starting the motor, and where a battery is part of the equipment of the ignition mechanism this starting is frequently done by merely placing the battery in circuit and retarding the spark to the limit, whereby the charge left in one of the cylinders when the motor is stopped is exploded and the motor caused to start without cranking.

In the present invention a hand lever is provided on the motor vehicle dash and so

connected with the ignition mechanism that the latter may be moved to retarded position, and when the hand lever is released, as would naturally be done after the motor had started, a spring retracts the ignition mechanism placing it in a predetermined advanced position for normal motor speeds. In the event the motor will not start "on the spark", provision is made for "cranking" and a connection is provided between the starting crank and the ignition mechanism whereby the spark is retarded while the starting crank is in engagement with the crank shaft and as soon as the motor has started and the crank is disengaged the ignition mechanism immediately adjusts itself to the advanced position. Thus it will be seen that the ignition mechanism is always in advanced position except when it is manually held in retarded position by the hand lever on the dash or by engaging the starting crank with the crank shaft.

The objects of the invention are to construct a motor vehicle having the characteristics above pointed out and to simplify the mechanism so as to make it positive in its action and simple to construct and maintain. These objects will be enlarged upon in the following specification and the details of the invention will be described therein.

In the drawings, Figure 1 is a side elevation of the forward part of a motor vehicle embodying the invention; Fig. 2 is a plan view of the same with the motor cylinders removed to more clearly illustrate the connections to the ignition mechanism; and Fig. 3 is an enlarged view of some of the connections illustrating another form of the invention.

Parts of the motor vehicle illustrated in the drawings may be designated as follows: 10, one of the front floor boards of the body, 11 the dash, 12 the radiator, 13 the front cross piece of the frame, 14 the motor, 15 the carbureter thereof, 16 the inclosed governor, 17 housed-in connections from the governor to the throttle, 18 the commutator or contact box which controls the timing of the battery ignition circuit, 19 the magneto driven by the motor having a rocking part 20 to control the timing of the magneto spark, and 21 the forward end of the motor crank shaft with which the clutch

teeth 22 of the starting crank 23 are adapted to engage.

Battery and magneto ignition systems are so well known that it is not necessary to 5 fully illustrate and describe them in this specification. It will be understood that the battery is suitably connected with the spark plugs of the motor and that the timing of the spark is controlled by a contact box as 10 shown somewhat diagrammatically at 18 and the movable part of this contact box may be rocked by a connecting rod 24 which is pinned to a hand lever 25 pivoted on a standard 26 mounted on the motor. This 15 standard has another arm 27 which operates a rock shaft 28 through a connecting rod 29, and an arm 30 on said rock shaft operates the rocking part 20 of the magneto, whereby the contact box 18 and the rocking 20 part 20 of the magneto are moved in unison for the purpose of advancing and retarding the spark in the motor. It will be understood that the contact box 18 and the rocking part 20 of the magneto control the 25 make-and-break of the low tension circuits of the battery and magneto, respectively, and that the high tension circuits are provided with suitable distributors for distributing the high tension current to the spark 30 plugs in the cylinders in proper sequence. Another arm 31 on the standard 26 is connected with a lever 32 by a rod 33, and the lever 32 is shown as pivoted to a bracket 34 on the frame piece 13, as at 35, and it is 35 provided with an opening through which the starting crank 23 loosely passes. A collar 34^a pinned to the starting crank shaft causes the lever 32 to be moved rearwardly as the starting crank is moved to engage 40 the crank shaft 21 of the motor, and this movement of the lever 32 rocks the standard 26, which in turn, through the various connecting rods and shafts, moves the contact box 18 and the rocking part 20 of the 45 magneto 19 to retarded position. A spring 36 surrounding the starting crank shaft between the lever 32 and the projecting portion 37 of the motor crank case 38 retracts the starting crank and the lever 32 and 50 thereby simultaneously disengages the starting crank and moves the contact box and the magneto to advanced position.

From the above it will be seen that the 55 spring 36 normally retains the starting crank in disengaged position and at the same time retains the ignition mechanism in advanced position, and the said mechanism may be temporarily shifted to retarded position by moving the hand lever 25 or by 60 moving the starting crank into engaging position with the motor crank shaft and in either case the ignition mechanism is immediately returned to advanced position when the motor starts or when the hand 65 lever is released.

In the form shown in Fig. 3 a spring take-up is provided in the rod 33, this rod being divided into two parts, 33^a and 33^b, each of which is provided with a lug 39 pinned thereon and having an opening 40 in which the other section is guided. A spring 41 tends to separate the rod sections and a stop 42 pinned to one of the rods limits the separating action. In said Fig. 3 the starting crank is shown in full lines in the position just as it is about to engage the motor crank shaft, having been moved from its fully retracted position, and the levers are so proportioned that the ignition mechanism is in full retarded position in this position of the starting crank 23. As the starting crank is moved to full engagement with the motor crank shaft 21 the ignition mechanism is still retained in its retarded position, but there is no further movement of said mechanism because of the take-up connection between the sections of the rod 33. Thus the ignition mechanism is insured of being in full retarded position even though the starting crank may be only partly engaged with the crank shaft as might be the case in the careless handling of the starting crank.

Having thus described my invention, what I claim is:

1. In a motor vehicle, the combination with a hydrocarbon motor having an adjustable spark advance mechanism and a spring to yieldingly retain said mechanism in advance position, of a free swinging lever accessible from the driver's seat for moving said mechanism to retarded position, the connections being such that the mechanism is returned by said spring to advanced position upon the release of said lever by the driver. 95
2. In a motor vehicle, the combination with a hydrocarbon motor having an adjustable spark advance mechanism, of a starting crank for said motor, and a spring on the starting crank and connected to said mechanism and to said crank for advancing the former and for disengaging the latter. 110
3. In a motor vehicle, the combination with a hydrocarbon motor having an adjustable spark advance mechanism, of a starting crank for said motor, connections from the starting crank to said mechanism for positively retarding the spark when the crank is engaged with the motor crank shaft, and a spring on the starting crank to disengage the same and having engagement with a lever of said connections to thereby advance the spark. 115
4. In a motor vehicle, the combination with a hydrocarbon motor having an adjustable spark advance mechanism, of a starting crank for said motor, connections from the starting crank to said mechanism for positively retarding the spark when the crank is engaged with the motor crank 125 130

shaft, and permitting the retarding of the spark independently of the engagement of said starting crank, and a spring on the starting crank to disengage the same and having engagement with the lever of said connections to thereby advance the spark.

5. In a motor vehicle, the combination with a hydrocarbon motor having a spark control device, of a starting crank for said 10 motor, and connections from said starting crank to said device whereby the initial movement of the starting crank toward engaging position fully retards said device and the continued movement of said crank 15 to full engagement serves to retain said device in retarded position.

6. In a motor vehicle, the combination

with a hydrocarbon motor having a spark control device, of a starting crank for said motor, connections from said starting crank to said device whereby the initial movement of the starting crank toward engaging position fully retards said device and the continued movement of said crank 20 to full engagement serves to retain said device in retarded position, and a spring to disengage said starting crank and to thereby advance 25 said spark control device.

In testimony whereof I affix my signature in the presence of two witnesses.

RUSSELL HUFF.
